UNITED STATES PATENT OFFICE.

EMIL A. HIRNER, OF ALLENTOWN, PENNSYLVANIA.

CAM MECHANISM FOR KNITTING MACHINES.

1,411,355.

Specification of Letters Patent. Patented Apr. 4, 1922.

Application filed September 19, 1918. Serial No. 254,797.

To all whom it may concern:

Be it known that I, EMIL A. HIRNER, a citizen of the United States, and a resident of Allentown, in the county of Lehigh and State of Pennsylvania, have invented certain new and useful Improvements in Cam Mechanism for Knitting Machines, of which the following is a specification, reference being had to the accompanying drawings.

10 My invention relates to cam and picker mechanisms for knitting machines, and is more particularly directed to that class of circular knitting machines employed for the production of seamless hosiery.

15 In such circular knitting machines, there are generally employed a multiplicity of needles movably mounted in radial slots or grooves in a so-called needle-cylinder. The stitch-forming activity of these needles involves up and down movement thereof relatively to the needle-cylinder, and such movement is commonly produced by cam surfaces on a cylinder concentric with the needle cylinder which engage appropriate projections (termed "butts") on the needles. To bring about this movement of the needles by the cam cylinder surfaces, the needle and cam cylinders are given a turning movement relatively to one another.

20 The formation or "fashioning" of the heel and toe portions of a stocking involves variation in the number of needles in action, and this is accomplished by periodically and successively shifting certain needles to such positions that they will not be acted on by the stitch-producing cam surfaces of the cam cylinder, and vice-versa. This operation is known as "picking",—the respective mechanisms or devices by which the needles are

25 put out of or into action being commonly designated and distinguished as "elevating pickers" and "depressing pickers". The necessary discrimination of the pickers between the needles to be picked and the rest is produced by differences in their butts,—

30 those picked being the "short butt" needles, and the others the "long butt" needles. During the fashioning operation, the relative turning movement of needle and cam cylinders which produces the stitches is oscillatory, while at other times it is one of continuous rotation.

My present invention is concerned especially with the picking by which the needles

are rendered inactive, and may be employed in connection with various well-known types of pickers for performing the reverse operation.

My invention is especially advantageous in permitting a closer grouping of the knitting cams and also the picking of long as well as short butt needles.

To this end my invention includes, in addition to the usual pair of stitch cams, mechanism wherein the functions of the center cam and the lifting picker are combined in a single device or unit, movable about a universal pivot, so as to be capable of being automatically shifted in either direction during oscillatory knitting.

My invention also comprehends a lifting picker, consisting of two relatively movable parts, with surfaces which conjointly form the engagement notch for the needle. Associated with the picker are means for normally maintaining the movable parts with their surfaces in fixed relation, but having capacity for permitting independent motion thereof to release the needles after the idle level has been reached.

The mechanism by which these results are attained will be best understood from the following description referred to in the accompanying drawings, in which

Fig. I is a plan view of a portion of a cam cylinder conveniently illustrating my invention.

Fig. II is a vertical sectional elevation of the same along the line II—II in Fig. I.

Fig. III is a plan section indicated by the arrows III—III in Fig. II.

Fig. IV is a similar view showing the moving parts in a different position.

Figs. V, VI and VII are detail perspective illustrations of the combined center cam and lifting picker.

Figs. VIII and IX are further details illustrating the construction of the same, these views being indicated by the arrows VIII—VIII in Fig. III and IX—IX in Fig. II respectively.

Figs. X to XIII inclusive are diagrammatic illustrations showing the relative position of the movable parts with respect to the stationary cam group during circular and oscillatory knitting.

As herein illustrated, the cam cylinder 1, is integrally formed with the usual bevel

gear 2, by which it may be actuated, either for rotation or oscillation in a manner already well understood. As best shown in Figs. X to XIII, the knitting cam group is 5 of the usual configuration, consisting of the stitch cams 3 and 4, symmetrically located with respect to the lower middle cam 5, the raising cams 6 and 7, and the guard cams 8 and 9.

- 10 The upper center cam 10, which, in general practice, is mounted in fixed relation, to the cylinder, is in the present instance capable of "floating" under the action of the needles from side to side and co-operating 15 with either of the stitch cams according to the direction of rotation of the cylinder. This freedom of action accorded the cam 10, is due to the peculiarity of its mounting, which consists in a pivot arrangement admitting of universal motion. Said cam is 20 integrally formed with an arm 11 (Figs. I to IX) extending outwardly through a V-shaped opening 12, in the cylinder wall, and is fulcrumed at 13, on the flattened downward extension 14, of the pivot post 15 (Fig. 25 V.) Said post is journalled for free oscillation in a bracket bearing 16, fixed to the cylinder, and is retained therein by means of a spring clip 17, as best shown in Figs. 30 I and II. This double pivotal mounting of the center cam 10 permits universal substantially bodily movement thereof, up and down or sidewise independently, substantially in the cylindrical plane of action of 35 the stitch cams 3 and 4, without substantial variation in the angular relation of its active end portion with reference to them, and likewise without variation of the inclination of its needle-guide surfaces. This simplifies 40 the movement of the parts, and tends to make their action quicker and easier.

It is to be noted that when the center cam 10, occupies an active position with respect to either of the stitch cams 3 or 4, (for example see Figures X and XIII), a substantially continuous cam edge is presented to the needles. In other words, the active edge of the center cam coincides substantially with that of the particular stitch cam 50 under consideration and is co-functional therewith in directing and guiding the needles. In this way, the jarring of the needles, which occurs at each change of the direction of their travel, is greatly lessened— 55 it being remembered that in the usual construction wherein the center cam occupies a fixed position between the two stitch cams, a break is occasioned in the knitting wave as the needles descend to form the stitch.

60 In order to perform the operation of a lifting picker in addition to its usual function, the center cam has been surmounted by a picker member 20, having recesses 21 and 22, and capable of a limited independent motion, as will be later described. The for-

ward edge of the member 20, is arcuate in profile, as seen from above, and when in the normal position illustrated in Fig. III it coincides with that of the cam 10 and is in tangential relation to the inner cylindrical 70 surface of the cam cylinder.

From the perspective figures of the drawings, it will be noted that the inner or forward portion of the cam 10, slightly overlaps the member 20 at each side, thereby 75 forming horizontal ledges or lifting surfaces which, in conjunction with the walls of the recesses 20 and 21, form the needle engaging notches. The member 20 is prolonged rearward or outwardly in the form of a dovetail shank 23, and fulcrumed about a double pivot consisting of the pins 24 and 25, which are fixed in the shank and project through an opening 26, of substantially semi-circular contour, in the arm 11 Fig. IX. Pins 24 80 and 25 are fixed at their lower ends in a block 27, which is subject to the pull of a spring 28, attached at its other end to the flattened downward projection 14, of the pivot post 15. The spring yieldingly maintains the member 20 in its normal position 90 with respect to the cam 10, which position is determined through the simultaneous engagement of the pins 24 and 25, with the straight edge 29 of the opening 26, in the 95 arm 11, as clearly shown in Fig. IX. The pins 24 and 25 become alternately functional as pivots depending upon the direction of motion induced in the member through the needles in operation. (See Figs. IV and 100 VII.) It is also to be noted that spring 28, in addition to the function above described, tends to hold the cam 10 yieldingly depressed as shown in Fig. II.

In order to restrain the independent action 105 of the member 20, until the needle has been raised to the idle level, I have provided the pivot post 15, with a laterally extending tongue 30, which plays in a slot 31, in the arm 11 of the cam 10, and is adapted to engage within a notch 32, in the outer end of the shank 23, of the member 20. The action 110 of these elements will be best understood by referring to Fig. II, wherein the member 20 is shown locked in central position with respect to the arm 11, by the action of the tongue 30. This relation obtains until the arm 11, is swung upwardly to an extent which will bring the upper edge thereof into coincidence with the upper edge of the 115 tongue (Fig. VI), whereupon the member 20 is released for independent movement under the action of the needle engaged within one of its recesses. After the member 20 has been swung to the requisite extent to 120 release the needle, it automatically returns to its normal position under the action of the spring 28. The vertical movement of the arm 11, of cam 10, is limited by a set screw stop 33. The adjustability of this 125 130

stop permits the adjustment of the positions at which the cam 10, comes to rest in its co-functional activities with the stitch cams 3 and 4, thereby permitting compensation 5 for wear upon the lower apex of the center cam as the needles move about the same.

The combined lateral and upward movement of the center cam 10 and the picker member 20 is controlled and guided by sliding 10 of the tips 40, and 41, of the picker member and the corresponding oppositely inclined needle guiding and stitch forming surfaces of the centre cam along the respective edges 42, and 43, of the stitch cam 15 blocks 3 and 4 whose inner faces constitute the stitch cams proper. The wear attending the guidance of the parts is thus restricted so as not to affect the needle-engaging portions of the cam 10, and the picker member 20.

The normal operative relation of the several cams for rotary knitting is shown in Fig. X, the direction of rotation of the cam cylinder being indicated by the arrow. The 25 long butt needles usually employed in stocking knitters are diagrammatically represented at 35, in solid black, and the short butt fashioning needles, as open rectangles at 36. During tubular knitting resulting 30 from the rotary operation, both sets of needles follow the common path represented in Fig. X in the well known way.

In Fig. XI, I have shown the position of the parts at the beginning of the first reverse 35 oscillatory movement of the cam cylinder 1 in knitting the heel or toe suture of the stocking. The long butt needles 35, have been elevated to the idle level in a known manner preparatory to the commencement 40 of the fashioning operation. As the cam cylinder 1 turns in the direction of the arrow, the butt of the first needle of the fashioning group 36, will engage within the recess 22, of the member 20, and carry said 45 member 20 along with it as shown in Fig. XII. The cam 10, will move with the member 20, it being at this time locked thereto by the tongue 30, as previously described, and the two will be bodily swung about the 50 universal fulcrum constituted by the pivots 13 and 15, under the guidance of the edge 42 of the cam block 3 which engages the cam 10 and the tip 40 of the picker member as already described. The cam 10 and the 55 member 20, will thus be moved in the angular direction indicated by the arrow in Fig. XII, until the level is reached at which the shank of the member 20, is freed from its engagement with the tongue 30, where- 60 upon the cam 10, will be held from further movement by the top screw 33, with the result that the picker member proceeds to swing independently also in the direction of the arrow about its pivot 24, to release the 65 said first needle 36 and deliver the same to

the guard cam 8, by which it is subsequently raised to the idle level. During this operation, the succeeding active needles 36 retain the cam 10, in the position illustrated in Fig. XIII, and the remaining fashioning 70 needles 36 follow the course determined by the knitting cams with consequent formation of stitches during the completion of this half of the oscillation of the cam cylinder 1. After the member 20 has swung to the maximum extent in releasing its charge to the 75 guard cam 8, it immediately returns to its normal position with respect to the cam 10, under the action of spring 28. When the needles have all cleared cam 10, the latter 80 will automatically resume the position shown in Fig. XI, in preparation for the succeeding movement of the cylinder in the opposite direction. The same cycle of operations will then be repeated in a reverse order, in a manner which will be obvious from the foregoing description.

It is to be particularly noted that the receiving recesses 21 and 22, of the picker member are comparatively deep so that long 90 butt needles may be picked with the same facility as the short butt needles. It is a characteristic of my invention that notwithstanding the lengths of the butts acted upon, the needles will all be elevated to a common 95 level, since the independent action of the picker member is confined to swinging in a horizontal plane. The added scope thus accorded the picker is advantageous in the production of certain classes of work where- 100 in the fashioning is carried beyond the median line at each side of the stocking. In such instances, certain of the long butt needles operate along with the short butt needles in effecting similar results.

My invention is of course to be associated with a suitable depressing picker mechanism by which the fashioning operation is completed. Such depressing picker mechanism may be of any standard type and for 110 this reason is not illustrated in the drawings.

Having thus described my invention, I claim:

1. In a circular knitting machine, the combination with a pair of stitch cams; of a center cam with active portion universally movable, substantially bodily, substantially in the plane of action of said stitch cams, and automatically shiftable into operative 120 relation with either of them during oscillatory knitting.

2. In a circular knitting machine, the combination with a pair of stitch cams; of a center cam with an active portion having 125 oppositely inclined stitch-forming needle-guide surfaces, and universally movable, substantially bodily, substantially in the plane of action of said stitch cams, in constant angular relation to them, so as to be 130

automatically shiftable to bring its said inclined surfaces into operative relation to one or other of said stitch cams alternately, during oscillatory knitting, without variation of 5 inclination.

3. In a circular knitting machine, the combination with a cam cylinder and a pair of stitch cams carried thereby; of a movable center cam with a supporting arm extending 10 out through an opening in the wall of the cylinder; a universal pivotal mounting for the outer end of said arm permitting automatic shifting of said center cam into operative relation with either of said stitch cams 15 during oscillatory knitting; and means for guiding the movement of said arm.

4. In a circular knitting machine, the combination with a cam cylinder and a pair of stitch cams carried thereby; of a movable center cam with a supporting arm extending 20 out through an opening in the wall of the cylinder; and a mounting for the outer end of said arm permitting universal substantially bodily movement of said center cam 25 substantially in the plane of action of said stitch cams, so as to render said center cam automatically shiftable into operative relation with either of said stitch cams, during oscillatory knitting, without substantial variation of angular relation to them.

5. In a circular knitting machine, the combination with a cam cylinder and a pair of stitch cams carried thereby; of a movable center cam with a supporting arm extending 35 out through an opening in the wall of the cylinder, and pivoted to swing horizontally and vertically about axes outside the cylinder.

6. In a circular knitting machine, the combination with a pair of stitch cams; of a double acting centrally mounted lifting picker with active portion substantially bodily movable, up and down or sidewise independently, substantially in the plane of 45 action of said stitch cams, and automatically shiftable in either direction during oscillatory knitting movement.

7. In a circular knitting machine the combination of a pair of stitch cams; a movable center cam capable of being shifted into operative relation with either of said stitch cams; and a double acting lifting picker member attached to said center cam and movable therewith and relatively thereto.

55 8. In a circular knitting machine, the combination of a pair of stitch cams; a movable center cam capable of being shifted into operative relation with either of said stitch cams; a double acting lifting picker member 60 pivoted to said center cam and capable of independent motion with respect thereto.

9. In a circular knitting machine, the combination of a pair of stitch cams; a movable center cam capable of being shifted into 65 operative relation with either of said stitch

cams; a double acting lifting picker member pivoted to said center cam and capable of independent motion with respect thereto, and means for locking said member and center cam in normal relation during the elevation 70 of the needle to idle level.

10. In a circular knitting machine, the combination of a pair of stitch cams; a movable center cam, capable of being automatically shifted into operative relation with 75 either of said stitch cams; an independently movable double acting lifting picker member, pivoted to said center cam; yielding means for depressing said picker member into the path of the fashioning needles during oscillatory knitting, so that, when the first needle of the series engages the picker member, the center cam will be moved substantially bodily therewith to be engaged by the succeeding needles; and means for holding 80 said cam and picker member in fixed relation during the first portion of their travel; capable of subsequently releasing said picker member from the center cam for independent motion in feeding the first needle to idle level.

11. In a circular knitting machine, the combination of a pair of stitch cams; a movable center cam capable of being automatically shifted into operative relation 95 with either of said stitch cams, and a supporting arm forming an integral extension of said cam; a pivot post parallel to the cylinder axis for the said arm; a double acting picker member having an integral shank 100 fulcrumed to the arm of said center cam; and a tongue forming part of said pivot post adapted to engage within a notch in the shank of the picker member to hold the latter in normal fixed relation with the center 105 cam, but permitting its release when a predetermined point in their combined travel has been reached.

12. In a circular knitting machine, the combination of a pair of stitch cams; a movable center cam capable of being automatically shifted into operative relation with either of said stitch cams, with a supporting arm forming an integral part of said center cam and suspended at its outer end 110 in a universal pivot; a double acting picker member supported for independent movement upon said arm; means for yieldingly holding said picker member normally in alignment with the center cam, said means 115 including a pair of spaced pins operating in alternation as fulcrums for the picker member, a straight edge adapted for co-operation with said pins, and a spring normally holding said pins in engagement with the 120 straight edge.

13. A picker device for circular knitting machines, consisting of two separate parts conjointly movable and operative as a unit in elevating the needle to the idle level, but 130

having capacity for relative independent motion to release the needle when it has reached the idle level.

14. In a circular knitting machine, the combination of a pair of stitch cams; a movable center cam capable of being shifted into operative relation with either of said stitch cams; and a double acting lifting picker member attached to said center cam and movable therewith; and an adjustable stop for limiting the vertical movement of the said center cam.

15. In a circular knitting machine the combination of a pair of stitch cams; a movable center cam capable of being shifted into co-operative relation with either of said stitch cams; a double acting lifting picker member movably mounted upon said center cam; and means locking the center cam and picker member as a single unit during the elevation of the needle to idle level, but thereafter permitting independent swinging of the picker member in a horizontal plane to release the needle.

25 16. In a circular knitting machine the combination of a pair of stitch cams; a movable center cam capable of being shifted into operative relation with either of said

stitch cams; a double acting lifting picker member movably mounted upon said center cam; means locking the center cam and picker member as a single unit during the elevation of the needle to idle level; but thereafter permitting independent swinging of the picker member in a horizontal plane to release the needle; and means for adjustably controlling the upward movement of the said picker member.

17. In a circular knitting machine, the combination of a pair of stitch cams; a movable center cam capable of being shifted into operative relation with either of said stitch cams; and a double acting lifting picker member attached to said center cam and movable therewith; a V shaped guide for determining the path of combined movement of the center cam and picker member and lugs formed on said picker member and adapted for cooperation with the said guide.

In testimony whereof, I have hereunto signed my name at Philadelphia, Pennsylvania, this 10th day of September, 1918.

EMIL A. HIRNER.
